UNITED STATES PATENT OFFICE.

THOMAS J. HATHAWAY, OF MONTEVALLO, MISSOURI.

WELL-DRILLING MACHINE.

SPECIFICATION forming part of Letters Patent No. 289,257, dated November 27, 1883.

Application filed September 20, 1883. (Model.)

To all whom it may concern:

Be it known that I, THOMAS J. HATHAWAY, of Montevallo, in the county of Vernon and State of Missouri, have invented a new and 5 Improved Well-Drilling Machine, of which the following is a full, clear, and exact description.

The object of the invention is to improve well-drilling machines, as hereinafter described, and pointed out in the claims.

Reference is to be had to the accompanying drawings, forming part of this specification, in which similar letters of reference indicate corresponding parts in all the figures.

15 Figure 1 is a sectional elevation of my improved drilling-machine. Fig. 2 is a horizontal section. Fig. 3 is a side elevation of the drill. Fig. 4 is an end elevation of the drill. Figs. 5, 6, 7, and 8 are details.

2c I arrange a stationary toothed rim, *a*, on the bed-frame *b* of a wagon, and fit a turn-table, *c*, around said rim for a pivot, and on rollers *a'* of bed-frame *b* for a support, to be turned by a team hitched to the sweep *d*, and 25 traveling around the wagon. The turn-table carries the tower or derrick *e*, from the top of which the drill-rope *f* is suspended by a pulley, *g*, over which the drill-rope passes from the drill-rope beam *h*, fitted on journals

30 having bearings in the uprights *i*, supported on the frame-piece *j* and by a couple of the tower-uprights *e*. The pulley *g*, over which the drill-rope passes, is mounted in the vertically reciprocating gate *k*, fixed in guideways 35 *l* at the top of the tower, and connected by rod *m* with a crank-pin, *o*, on the drum *p*, fitted loosely on the driving-shaft *q*, and connected to said shaft by the internally-toothed flange *s* of the drum and the spring-pawl *t* of the hub *u*, keyed to the shaft *q* inside the drum, which arrangement enables the drill to be 40 worked when the shaft *q* is turned forward, and allows the drill to rest when the said shaft is turned backward. This mode of connecting the drum *p* to the hub *u* is also employed in order that the connecting-rod *m* will fall instantly after passing the upper center of the crank-pin, to allow the drill to strike properly, the fall taking place when the thrust of

45 the weight of the drill, rope, rod *m*, and the pulley and its frame passes from the rising to 50

the descending side of the drum and in the direction the pawl *t* drives. The shaft *q* also carries a loose bevel-wheel, *v*, that rests when the shaft *q* turns forward to work the drill, 55 and is engaged by its toothed face *y* and the spring-pawl *w* of hub *x* when the shaft *q* turns backward, and then turns the beam *h* by the wheels *z*, *a'*, and *b'* to raise the drill out of the well when required, the team being then 60 driven the reverse way around the machine—that is to say, to the left hand. The shaft *q* is arranged in suitable bearing-supports, *c'* and *d'*, on the turn-table, and has a toothed pinion, *e'*, that gears with the stationary toothed rim *a*, and causes the shaft *q* to revolve when the turn-table is revolved by the team. A stop-latch, *f'*, is arranged on one of the uprights *i* in connection with toothed wheel *b'*, to prevent the drill-rope from unwinding from the 70 beam *h* faster than required, and a lever, *g'*, having a stop-latch, *h'*, is fitted on the journal of the rope-beam *h* in relation to wheel *b'*, whereby the turning of the rope-beam to let out the drill-rope from time to time as the drill works down may be controlled, to prevent the overrunning of the beam by the weight of the rope. These latches *f'* and *h'* have the usual 75 trip-handles, *j'*, for disconnecting them from the wheel, and springs or other means to keep them in connection with the wheel.

When the drill is to be let down into the well from the surface of the ground, or any other considerable distance, it is to be done by turning the machine forward or allowing it to be 85 turned forward by the weight of the drill, the wheel *v* being keyed fast to the shaft, and the spring-pawl *t* of the crank-pin hub *p* being secured in any way to prevent it from engaging ratchet-rim *s* at that time, and the stop-latches *f'* and *h'* being disconnected from 90 wheel *b'*.

To prevent the overrunning of the machine by the weight of the drill when thus lowering it, I have attached a smaller sweep or lever, 95 *k'*, to the turn-table in advance of the sweep *d*, to which the horses are hitched, to which lever *k'* the holdback-gear of the harness may be connected for regulating the descent.

For a derrick to suspend the sand-pump rope 100 *l* when the drill is removed from the well, I have provided an arm, *m'*, to swing from the

pivot n' on one of the uprights e , said arm having the pulley o' hanging from it over the well when the said arm is properly adjusted, and being temporarily secured in position by 5 a notched keeper, p' , pivoted to another of the uprights e , and crossing and dropping onto arm m' suitably for holding it. The sand-pump rope runs from the pulley o' to the windlass q' , whereon it is wound and unwound to 10 operate the pump. When the pump is to be removed, the keeper p' is detached from the arm m' , and the said arm is swung back out of the way of the drill-rope.

My improvement of the drill consists of two 15 parts, t' , each having a radial bit, u' , and a circumferential bit, v' , and being placed side by side along the center line, w' , so that the two bits, u' , substantially form the ordinary plain drill-bit, the width of which corresponds 20 to the diameter of the well to be drilled, and the bits v' form curved lips to the outer corners of the bit u' , which cut along the circumference of the hole and materially facilitate the work. The two parts each have a shank, 25 x' , which together are suitably shaped to form a dovetail, and are fitted to the dovetail-shaped notch y' in the lower end of the drill-stock z' , where they are secured by the band a^2 , which drops on the taper shank of the stock 30 to the required position for keeping them in place, and is raised above said shanks when the drill-bits are to be taken out. At the upper edge of the band a^2 , which fastens the bits, there is to be a hole for a key, b^2 , to fasten the 35 band, one-half of said hole being formed in the shank of each bit, which secures the bits firmly by keeping the band in position.

In this improved drilling-machine the hand 40 for turning the drill in the hole by the rope will be dispensed with, because the drill and the rope are turned by the rotation of the turn-table for working the drill, the length 45 of the stroke of the drill will be the same whether the team goes fast or slow, and the saving in time and labor by the arrangement of the drill to be worked on the wagon-bed without unloading or taking apart will effect 50 considerable economy in the working of well-drilling machines. The machine is also applicable for driving well-boring augers by taking off the connecting-rod m and arranging 55 a cross-bar, b^2 , having a socket, c^2 , for the shank of the auger across the center of the turn-table, so that the rotation of the turn-table by the team will turn the auger. The sweeps d and k' are pivoted to the turn-table at d^2 and e^2 , to enable them to be swung up to 60 the tower and be secured thereto by cords when the machine is to be transported along

Having thus described my invention, I claim as new and desire to secure by Letters Patent—

1. The combination, with a wagon-bed frame having the rollers a^3 , of a stationary toothed rim, a , a turn-table, c , pivoted on said rim, a tower, e , arranged on said table, and a device, d , to which horses may be hitched, 65 as shown and described.

2. The combination, with the tower e , of the drill-rope f , the pulley g , the journaled beam h , the uprights i , the frame j , the reciprocating gate k , arranged in guides l , the rod m , the drum p , having crank-pin o fitted loosely on drive-shaft q , and provided with internally-toothed flange s , and the hub u , 70 carrying spring-pawl t , whereby the drill may be operated, as described.

3. The drill-rope f , extended from the rope-beam h over the vertically-reciprocating pulley g , connected to and operated by the crank-shaft q , and being connected thereto by an escapement device, enabling the drill to fall when the crank-pin has passed the upper center, substantially as described.

4. The combination, in a well-drilling machine, of the drill-rope f , beam h , pulley g , sliding gate k , connecting-rod m , and the driving crank-shaft q , substantially as described.

5. The drill-rope beam h , geared with the 80 driving-shaft q , by the ratchet-faced wheel v , pawl w , collar x , and the intermediate gears z , a' , and b' , the ratchet and pawl being arranged to disconnect when the shaft q turns forward to work the drill, and to connect and 95 raise the drill when the driving-shaft is turned backward, substantially as described.

6. The combination of the stop-latch f' , lever g' , and stop-latch h' , with the toothed wheel b' on the rope-beam h , substantially as 100 described.

7. The combination of the shifting sand-pump derrick m' and p' with the drill-rope 105 tower e , and the sand-pump rope l' , substantially as described.

8. The improvement in well-drills, consisting of the drill made in two parts, t' , each having a radial bit, u' , and a circumferential bit, v' , said parts being placed side by side, and secured in the drill-stock together, substantially as described.

9. The drill consisting of two parts, t' , each having a taper shank, x' , forming together a dovetail shape, and being secured in the dovetail notch y' of the stock z' by the band a^2 , substantially as described.

THOMAS J. HATHAWAY.
